UNITED STATES PATENT OFFICE

WALDEMAR F. ANDERSEN, OF ALAMEDA, CALIFORNIA

ADVERTISING MACHINE

Application filed January 15, 1929. Serial No. 332,671.

This invention relates to an advertising machine, and its object is to produce a machine which will have space for sufficient interesting general matter, such as in the present instance a clock to make the machine attractive to the public, and to provide space for two types of advertising whereby the machine may be made attractive as a whole to the person or concern desiring to make use 10 of a particular part of it.

In the present instance the machine is provided with a plurality of small triangular carriers, each of which takes a menu card, in addition to which the machine is provided 15 with a series of larger display cards whereby the person making use of the machine for the display of the menu card can obtain a revenue from the machine from an entirely distinct form of advertising card carried by it 20 so that the machine as a whole will be more useful than it would be if it would not have the separate kinds of cards.

Another object of the invention is to so arrange the movement of the cards that one 25 set of cards is standing still while another set of cards is moving from one position to a new position. This synchronization of the changes being made for the purpose of having one set of cards or advertisements quiet 30 during the time the other set is being shifted so that the person observing the advertising will not be as much disturbed in looking at the advertising as he would be if both sets change at approximately the same time. In 35 other words, if a person is reading one set of cards he can continue reading that set of cards during the time the other display is changing, or vice versa.

Another object of the invention is to provide 40 the maximum number of changes on the rotary advertising drum for the space occupied, the triangles used turning very close together and being of the minimum thickness for a plurality of advertisements.

Another object of the invention is to provide 45 for the accurate timing of all of the display cards, and for a driving device which will not injure any part of the machine if through an accident a jam in the operating 50 mechanism should occur.

Another object of the invention is to provide a form of carrier for the cards which will be easily changed as to subject matter, and a form of carrier for the larger cards which will be standard in size and always move to the same position when the cards are shifted from one place to another place in the series.

Another object of the invention is to provide the machine with one type of movable sign at one portion thereof, while another type of movable sign is exposed at another place, the movement of one sign being timed with respect to the other sign, so that one sign is always at rest during the time the other is changing, and vice versa.

The object of this arrangement is to have one change going on more or less at all times, whereby the attention of the passer-by is attracted, and when so attracted he can read the material carried by the stationary signs.

Another object of the invention is to provide a timing device which will allow an adequate space of time between the movements of each sign for the comfortable reading of the material carried, in the present instance the menu cards, or whatever may be put upon the rotary drums, is intended to be in large letters which can be individually and quickly read, which drums change three times, while the cards in the advertising frames change only once, thereby giving a person time to read the more extended matter carried by the cards.

Other objects of the invention will be apparent as the description proceeds.

An embodiment of the invention is shown in the accompanying drawings in which the same reference numeral is applied to the same portion throughout the several figures of the drawings, and of which there may be modifications.

Figure 1 is a front elevation of the complete machine,

Figure 2 is a side elevation of the complete machine,

Figure 3 is a front elevation of the machine with portions broken away to illustrate the inner working mechanism, the number of ad-

vertisements being cut down to enable the scale of the machine to be made larger.

Figure 4 is a back elevation of the frame work of the machine showing the operating mechanism,

Figure 5 is a side elevation of the operating mechanism on a larger scale, certain of the advertisements being omitted for purposes of illustration,

Figure 6 is a detail view of a modified form of the driving mechanism on a slightly larger scale than Figure 5,

Figure 7 is a side elevation of the rack for carrying the card holding frames,

Figure 8 is a plan view of a series of the card holding frames showing the means for holding them in a fixed position to be acted upon by the shifting mechanism,

Figure 9 is an edge view of a portion of the top of one of the card holding frames,

Figure 9^a is a view of the upper corner of one of the card holding frames showing the lug for picking the frames up,

Figure 10 is a side elevation of the timing gear,

Figure 11 is an edge view of the gearing shown in Figure 10,

Figure 11^a is a sectional view of one of the friction driving devices,

Figure 12 is a side elevation of one of the triangular advertisement carriers,

Figure 13 is an end view of the carrier shown in Figure 12,

Figure 14 is a side elevation of one of the sprockets for carrying the chains to shift the card holding frames,

Figure 15 is a vertical sectional view of the same sprocket wheel,

Figure 16 is a side elevation of a slightly modified form of the invention in which the card frames pass entirely across the front of the triangular frames and

Figure 17 is a front elevation of the same machine, portions of each of the latter figures being broken away for purposes of illustration.

The present advertising machine is of the class of machine in which a portion of the display rotates, while another portion of the display is on cards which are bodily moved out of the vision of the onlooker and transferred to the back of a stack of cards to be continuously and repeatedly displayed to the public.

Looking at the outside of the machine, it is provided with a face 1, and with a plurality of round columns 2 at its corners, which corners may be themselves rounded, or ornamented in any desired way. The ends of the case are indicated at 3 and the lower portion of the front 4 is mounted on two hinges 5 and 6 to permit a convenient inspection of the entire interior apparatus. At the top there is a door 8, which is mounted upon two concealed hinges 9 and 10 to permit the upper

portion of the top to be opened in the same way as the lower portion. A fixed bar 12 extends across the front just in back of the lower front door, while a plate 13 covers the space between the two sets of revoluble menu cards to conceal the opening between them as will be illustrated in a later view.

The top of the machine is flat, and is carried by the ends and posts being indicated at 16.

The front door 8 is also provided with a clock space 17, or said door may be provided with any other more attractive material which will continuously attract persons to look at the entire advertising machine.

The operating frame of the machine proper sets upon the base 1, and consists of four vertical standards 17, 18, 19 and 20 which are spaced apart laterally by means of two rods 21, 22 at the top, and two similar spacing rods 23, 24 at the bottom. From front to back the rods 17, 18 and 19, 20 are secured in a fixed position by extending into the sockets 21 to 24 on the ends of the plates 25, 26 and 27, 28 which plates have sockets at their rear

ends as indicated at 29 with respect to the plate 25 for each one of said plates, there being four sockets, and four plates at the front of the machine, while the same plates have four sockets at the rear of the machine to take the end of the members 17 and 19.

The standards 18 and 20 are sufficiently heavy to provide bearings for the shafts 30, 31, 32 and any other shaft that may extend through said standards.

The present machine has six of the rotary sign card holders.

The shafts 30, 31, 32 all extend through the two side standards, and each one of them has a gear on one end as indicated at 33, 34 and 35, which gears are in mesh with the vertical gears 36, 37 and 38, the latter gears being carried by the vertically extending shaft 39 and driving all of the rotary advertisement carriers. The vertical shaft 39 is driven from the gear 37 by means of a bevel gear 40 on the horizontally extending shaft 41, which shaft has the bevel gear 42 thereon, in mesh with the bevel gear 43 on the vertical shaft 44.

Yokes 45, 46 hold the shaft 41 and its associated gears in the proper relation to their driving members and driven members, and a friction clutch enclosed with the casing 47 affords means for driving the machine without danger of breaking should any part fail to act properly. The clutch 47 consists of a shaft 44 secured to the hub of a flat casing 45. The flat casing 45 has a cover 46 secured thereto by suitable screws 47 and a hub 48 through which the shaft 49 passes, said shaft 49 being secured to the plate 50 at its end, which plate is normally held in engagement with the part of the clutch to which it is to be applied by means of the spiral spring 52.

There is a similar friction clutch within the casing 53 to prevent any danger of injury to the machine should any part become stuck.

The shaft 49 passes through a bearing 54, and it is connected at its lower end to the hub of a bevel gear 55 which is in mesh with a bevel gear 56 which is on a shaft extending into the stop gear mechanism within the casing 57. The upper end of the shaft 44 is journaled in a plate 58, which also has an opening therethrough to carry the shaft 59, on the top of the clutch member 53, the same as the member 47.

Depending from the friction driving mechanism 53 is a shaft 60 which is journalled in a bearing 61, and carries the bevel gear 62 in mesh with the bevel gear 63 on the shaft 84 running into the stop gear casing 57, the same as the shaft for the operation of the gear 56.

The shafts 30, 31 and 32, and the other shafts carry the rotatable drums as indicated in Figure 3, and the advertising drums which are carried by them are shown at A, B, C, D, E and F in Figure 3, a number of the drums being omitted for purposes of illustration.

The driving mechanism is shown within two casings, the casing 57 within which is installed the timing mechanism for the rotary triple advertising drums, and the casing 70 which simply carries a worm and worm wheel for operating the gears within the casing 57 at the proper speed.

The motor 72 is mounted somewhat above the base 1 on a portion of the frame work of the machine, and it has a belt tightener 73 supported by the standard 74 and links 75 to hold the belt thereon in proper driving relation to the wheel 71 driving the worm inside the casing 70. The belt is indicated at 75 and it passes around the pulley 76 on the motor 72, and under the pulley 73 and around the pulley 71 on the shaft carrying the worm within the casing 70. This worm drives the worm wheel indicated in dotted lines in Figure 4 at 76, and said worm wheel in turn drives the stop gear mechanism.

The casing 57 forms an enclosure for the stop mechanism driven by the shaft 77, and it has an enclosing side plate 70 to retain lubricant therein. The shaft 77 carries two disks 78 and 81, the disk 78 having a pin 79 projecting therefrom at a flat plate 80 in a disk 81. At the side of the disk 81 there is a gear 82 on said shaft 77 for driving the small gear 83 on the shaft 84 which carries the bevel gear 63.

The pin 79 is arranged to pass into any one of six slots of the disk 85, which slots extend radially and which arms thus produced have curved places at each arm as indicated at 86 upon which the periphery of the disk 81 slides when the disk 85 is standing still. The disk 85 is secured to the shaft 87, and it has a gear 88 thereon which is in

mesh with a small gear 89 on the shaft 90. The shaft 90 has a bevel gear 56 to drive the rotary advertising drum.

The rotary advertising drums are made triangular in shape to give the most compact changing form for the number of advertisements used, as indicated in Figures 12 and 13, and consist of sheet metal triangular prisms with faces 91, 92 and 93 having card retaining cleats 94 at each edge made of sheet metal, and at the middle there is a strap 95 to prevent the cards from bulging, each side of the drum being made the same as the other side.

At the top of the frame work just described, there are four standards 100, 101, 102, 103 which are bolted to the members 25 and 26 to form a frame work for the support of the card advertising frame. The standards just mentioned are connected together back and forth by means of four plates 105, 106, 107 and 108, while just below the plates 25 and 26 are two other plates 109, 110 which aid in forming the channel in which the card frames are moved. Two bars 110, 112 are connected to the bottom of the bars 109, 110 and form a base upon which the card frames 113, of which there are a number, rest. Two vertical bars 114, 115 form the front of the cage in which the card frames operate, and these bars are connected to the cross bar 112 at their lower ends, and to the plates 116 to 118 inclusive at their middle portion and upper ends respectively. The plates 116 to 118 being in turn connected to the flat bars 105, 106, and 107, 108 which are carried by the standards 101 to 103 respectively.

For the transference of the card carrying frames 113, two sprocket chains 120, 121 which have pins as indicated at 120', 121' to engage the ears on the frames 113 are used, as will be later explained. Each of the sprocket chains is supported in precisely the same manner, passing around four sprocket wheels 123, 124, 125 and 126. These sprocket wheels are shown in Figures 14 and 15, and they consist of a hub 127 carrying the sprocket teeth 128 and are revoluble on a short stud shaft 129, which stud shaft is carried by the adjacent flat bar of the series 105, to 108.

A set screw 130 passing through the hub 127 into a groove 131 of the stud shaft holds the sprocket wheels in place, while a nut 132 on the outside of the supporting bar 105 holds the stud shaft locked securely in position, and for the lubrication of the sprocket wheels each one is provided with a small oil cup 133.

At the top and back end of the plates 105, 106 each sprocket wheel is connected to its shaft and to a gear 134, there being two such gears for the purpose of insuring the equal drive without twisting of both of the chains 120, 121. The two gears 134 are in

mesh with a gear 135 and another gear 136, which gears are carried by the shaft 137 and driven from the small bevel gear 138. The gear 138 is in mesh with a small bevel gear 139 on the shaft 140, said shaft being journaled at the top and bottom of a V-shaped yoke 141, which yoke is secured to the flat plate 105. A rod 142 connects the upper ends of the front pair of standards 102, 103, while another similar rod 143 connects the upper ends of the rear pair of standards 100, 101 to give stability to the machine. A universal joint 143 connects the shaft 59 with the shaft 140, while another universal joint 145 connects the shaft 144 with the shaft 40, whereby the two chains are driven in unison.

In order to insure the proper placing of the card frames 113, they are provided with inverted V-shaped ears 113' at opposite upper corners and to insure the proper placing of the signs 113 when they are returned back to the stack of frames there are two vertical bars 146, 147. These bars have their upper ends bent forwardly as indicated in Figure 5 at 148. These bars are welded to four short plates 149, 150, 151, 152, said plates being, in order, carried by the rear end of the plates 105, 107, 108, 106. The upper ends 25 of the bars 146, 147 are bent forwardly for the purpose of pushing the lower end of the card frames 113 as far back as possible to insure causing them to pass down behind the whole set of frames when one frame is being 30 transferred on the chain.

In order to restore the proper placing of all of the frames of the set, it is necessary to provide means whereby the entire set of frames are to be pushed forward when they 40 are all together, and this is accomplished by having the pins on the chains which pick up the card frames engage the upper ends of two levers 152', 153', said levers being pivotally mounted on the plates 109, 110, respectively. These levers have rearwardly extending rods 154, 155 which at their rear ends connect to two levers 156, 157. In order to steady the action of the two levers 156, 157, they are connected by a rod 158 which rod 45 also pushes the entire set of plates forwardly.

In order to hold the set of frames forward when pushed forwardly by the action of the rod 158 there are two spring latches 159, 55 159' which engage the rear frame of the set to hold all of them forward during the time the pins on the sprocket chain are shifting the front frame from its position at the front of the set of frames, to its position 60 at the rear of the set of frames. These two spring latches are carried by the standards 100, 101 respectively.

In order to hold the top of the two front plates 113 in the proper position to be engaged by the pins on the two sprocket chains,

there are two levers 160, 161 which are pivotally mounted on the top of two posts 162, 163 to bear frictionally upon the edges of the two forward plates of the series to hold them properly positioned to be lifted by the chain. 70 These two levers have short levers 160', 161' connected thereto which are also connected to spiral springs 164, 165 which springs are in turn connected to the posts 102, 103 to cause the levers to engage the edges of the plates 75 with sufficient frictional force to hold them in the proper position. Two plates 158' and 159' hold the frames 113 in position to be pushed into the hooks or latches 158, 159.

In order to restore the apparatus for holding the frames in the proper position to its initial position after having been engaged by the pins on the chains, the levers 156, 157 are carried by a shaft 166 which shaft has a depending arm 167 connected to a link 168, 85 said link in turn being connected to a rod 169 which compresses a spiral spring 170 carried by two bearings 171, 172. The result of the foregoing construction is that as soon as the pins on the chain let go of the two arms 90 152, 153 that they will be restored to the initial position shown in Figure 5, but in that time the latches 158, 159 will have caught the entire series of card frames and will hold them snugly up against the front plate. 95

Where a more flexible drive than that shown in Figure 5 is desired, the drive shown in Figure 6 may be used. In this figure the lower portion of the gear changing apparatus is the same, and the two friction driving 100 clutches 47, 53 are the same, but the two friction clutches are then provided with the universal joints 180, 181 which are connected in turn to the shafts 182, 183 and they are in turn connected to universal joints 184, 185 105 which extend to the upper portion of the machine.

In Figures 16 and 17 there is shown a slightly modified form of the invention, in which the stack of card frames is accumulated at the bottom of the machine, and all of the frames are carried one by one up the front of the revolute drums. The frames are then transferred to the back of the machine in back of the clock, the chains operating a timing device with respect to the drums which will change the triangular drums immediately after the card frame disappears from view. In this form of the invention, the outer casing of the apparatus is indicated at 110 200, and may be of any desired type to enclose the frame work of the machine, which frame work consists of four flat bars 201 to 204 on each edge of the casing, and which bars have holes therein to form journals for 115 all of the horizontally extending shafts. The bars 201, to 204 are duplicated on opposite edges of the machine, and are connected to the top and bottom of said casing 200. The bars 202 have a depending bar or bracket 120 125

205 with a horizontal lug 206 to carry the spring 207.

The spring 207 engages notches in a disk 208 which is on the shaft 209, said shaft also 5 carrying a bevelled gear 210, which engages a small bevel gear 211 on the upper end of the shaft 212. The shaft 212 is journalled in bearings 213, 214. The shaft 212 carries a plurality of gears 215 in mesh with the gears 216 on the ends of the horizontal drum shafts 217, of which there are eight.

In the present instance there are eight of the drums A to H inclusive with space enough between the fronts of the drums and the front 15 casings to permit the sprocket chains 218 to pass and carry the advertising plates 113, the plates being carried in substantially the same manner as in the previous form of the invention, each plate having a lug 113' at its upper 20 corners the same as in the other form of the invention. In the present instance there are eight of the sprocket wheels 220 at the four corners of the frame, the same as in the other form of the invention, except that in the 25 present instance the frame is longer, and the space between the top of the frame and the bottom of the frame is sufficient to provide space for all of the rotating drums, the frames 113 moving from the bottom of the casing to 30 the top of the casing before any movement of the rotating drums takes place. This machine is driven from the motor 221 which has a worm 222 in mesh with a worm wheel 223, the latter having a small sprocket gear 224, 35 which drives a chain 225 which passes around a small sprocket wheel 226 on a shaft 227. The shaft 227 also carries a spur gear 228 in mesh with a spur gear 229 on the shaft 230 which carries the lower sprocket gear 220 at 40 the back of the machine.

In order to drive the chain equally from both sides the shaft 227 extends entirely across the machine, and has a spur gear on its other end as indicated at 228' in mesh with a 45 gear 229' on the stud shaft carrying the sprocket gear 220 at the back of that side of the machine.

The operation of the machine will be seen from the foregoing.

50 Upon the operation of the motor the two spur gears 220 at the back and rear of the frame will be rotated to cause the chain 218 at both sides of the machine to travel downwardly at the back of the machine. This 55 will cause the pins 218' to engage the frames 113 at the bottom of the machine and carry them upwardly in front of all of the triangular drums, said chains being spaced from the drums far enough to permit the drums to turn 60 over without interferences, and when the pins 218' strike the two cams 208 on the shaft 209 at the top of the machine, that shaft will be turned $\frac{1}{6}$ th of a revolution which will turn the triangular drums exactly one-third owing 65 to the ratio of the gears 210, 211, whereupon

the frame will be carried down to its original position. The same apparatus for placing the frames in position may be used with this form of the invention as with the other.

Having thus described my invention, what I desire to secure by Letters Patent of the United States is as follows, but modifications may be made in carrying out the invention as shown in the drawings and in the above particularly described form thereof, within the purview of the annexed claims:

1. An advertising machine comprising a frame, a plurality of rectangular card carrying frames, each frame having lugs on opposite ends for picking the same up, a chain at opposite ends of said frame, means on each chain to engage the lugs of the frames to lift them one frame at a time out of the stack of frames and restore them to the rear of the stack of frames, means to push the stack of frames forwardly, means to hold the frames in a given position, and means to strike the frame at its top when it is being restored to the position at the back of the stack of frames to insure its proper placement in the stack. 90

2. An advertising machine comprising a frame having an open front portion and a covered front portion, a stack of card carrying frames in the lower end of said frame exposing the outside frame of said stack to view in 95 said open front, a plurality of pivoted card carrying frames above said stack of frames and visible through said open front, means to raise one of said frames from the stack and carry it up in front of the pivoted frames and 100 back of the covered portion, means to revolve the pivoted frames in unison as the frame goes behind the covered portion, and means to return the frame to the back part of the stack. 105

3. An advertising machine comprising a cabinet frame having an open front portion and a covered front portion, a stack of card carrying frames in the lower part of said frame, the front card in said stack being displayed through said open front, a plurality of 110 revoluble drums each drum having several advertising faces mounted above said stack and displayed through said open front, an endless chain having projecting pins on each side of said stack and extending to the top portion of said frame, said pins adapted to engage lugs on the sides of said frames to carry them up in front of said revoluble drums and behind the covered portion, means 115 on the chain for rotating said drums to bring new faces to view after said card frame has disappeared from view, means to return the frame to the back of the stack by the travel of said chain, and means to drive said chain. 120

In testimony whereof I have hereunto set my hand this 10th day of January, A. D. 1929.

WALDEMAR F. ANDERSEN.
